ENGINE STARTER

John W. Fitz Gerald, Milwaukee, Wis., assignor
to Briggs & Stratton Corporation, Milwaukee,
Wis., a corporation of Delaware

Application March 30, 1940, Serial No. 327,059

8 Claims. (Cl. 74—7)

This invention relates to engine starters and the like the copending application of John W. Fitz Gerald, Serial No. 327,058, filed Mar. 30, 1940, has, as its broad general object, the provision of means for holding the pinion of a so-called automatic type starter in mesh with the engine ring gear until the engine has been fully started.

As explained at length in said copending application, the automatic type of engine starter in which the pinion is automatically propelled into mesh with the ring gear and automatically retracted has the disadvantage of de-meshing substantially immediately after the first explosion in the engine so that in engines which start hard, the starting cycle must be repeated several times.

In the manual type of engine starter in which the pinion is manually moved into mesh with the ring gear and held in mesh as long as the starter pedal is depressed, there is the danger that the overrunning clutch which is provided to allow the pinion to spin when the engine starts, often sticks and as a consequence, the starter armature is revolved at speeds apt to cause damage to the armature.

This invention, like that forming the subject matter of the aforesaid copending application, therefore, contemplates the provision of means for preventing retraction of the pinion in an automatic type of starter until the engine is actually operating under its own power but without danger to the starter motor.

The specific purpose of the present invention is to provide means for controlling pinion retraction from some function of the engine.

With the above and other objects in view, which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates several complete examples of the physical embodiment of the invention, constructed in accordance with the best modes so far devised for the practical application of the principles thereof, and in which:

Figure 1 is a side view of an engine starter embodying this invention, said view showing the pinion in mesh with the ring gear;

Figure 2 is a side view of part of the starter mechanism illustrating a modified form of pinion control; and

Figures 3 and 4 are views similar to Figure 2 illustrating two other modified embodiments of the invention.

Referring now particularly to the accompanying drawing, in which like numerals indicate like parts, the numeral 5 designates the ring gear of an engine to be started by the starter mechanism, indicated generally by the numeral 6. The starter mechanism comprises a pinion 7 mounted to move longitudinally along a motor driven power shaft 7' to and from an operative position meshing with the ring gear.

The entire starter mechanism is mounted as a unit on the shaft 7'. Besides the pinion 7, it comprises a pinion actuating screw 8 coupled to the power shaft through a torsionally and endwise resilient coupling, indicated generally by the numeral 10.

The specific construction of the coupling forms no part of this invention and may be like that illustrated in the John W. Fitz Gerald Reissue Patent No. 20,686, issued April 5, 1938, for Engine starter.

The actuating screw 8 is externally threaded and is received in an internally threaded sleeve 11 extended from the pinion. Hence, upon relative rotation between the screw and the pinion, the pinion is propelled into mesh with the ring gear or retracted, depending upon the direction of the speed differential.

The objectives of this invention may be accomplished in several ways and in the method employed in the structure shown in Figure 1, a detent or latch pin 12 is arranged to drop into an annular groove 13 in the pinion sleeve when the pinion is fully meshed with the ring gear.

The pin 12 is constrained to axial motion and held against displacement in any suitable manner so that when it engages in the groove 13, as shown in Figure 1, retraction of the pinion is prevented.

Hence, by making withdrawal of the pin 12 dependent upon some function of the engine in full operation, the starter can be held in mesh until the engine has been properly started. One such function of the engine is intake manifold suction.

To utilize this function of the engine, the pin 12 has a piston 14 connected thereto which reciprocates in a cylinder 15. The cylinder is connected through a duct 16 to the intake manifold. Consequently, when the engine begins to operate under its own power, the suction in the intake manifold becomes strong enough to lift the piston 14 and consequently, the locking pin to inoperative position.

While gravity may be depended upon to engage the pin in the groove, if desired, a light spring 17 may be interposed between the piston and the head of the cylinder.

5 Another engine function which is readily adaptable to control of the pinion is oil pressure, and in Figure 2 one manner of utilizing oil pressure to lift the pin 12 out of the groove is illustrated. As here shown, the cylinder 15 may be
10 connected through a duct 18 with the oil line on the pressure side of the pump so that oil pressure lifts the piston 14 to raise the locking pin out of the groove.

To prevent dashpot action, the cap 19 which
15 closes the open end of the cylinder is provided
with an air bleed.

The output of the generator also may be used to lift the locking pin out of the groove, and one simple manner of utilizing this function of the engine is illustrated in Figure 3. For this purpose, it is only necessary to provide the pin with a solenoid plunger 20 which moves axially into a solenoid coil 21 upon energization of the coil.

The coil may be connected with the electric system of the engine in any manner as long as the energizing current is dependent upon operation of the generator. With this form of the invention, it is preferable to have the locking pin 12 formed of nonmagnetic metal.

30 Still another manner of controlling the pinion from the engine is to provide a vane 22 pivoted, as shown in Figure 4, behind the cooling fan 23 so that the blast from the fan tilts the vane about its pivotal mounting. A suitable system of levers 24 utilizes the motion thus produced

35 to lift the locking pin out of the groove 13.

40 From the foregoing description taken in connection with the accompanying drawing, it will be readily apparent to those skilled in the art, that this invention provides an exceptionally simple manner of holding the starter in mesh until the engine actually begins to operate under its own power.

What I claim as my invention is:

45 1. An engine starter of the type having a pinion automatically movable into mesh with the ring gear of an engine to be started and automatically retractable upon starting of the engine: characterized by the provision of releasable latch means for holding the pinion in mesh; and means responsive to a source of energy remote from the starter for releasing said latch means.

means.

2. In a starter for internal combustion engines, the combination of: an engine carried gear; a pinion; means for automatically moving the pinion into mesh with the engine gear and for driving the engine gear to effect cranking of the engine and for automatically retracting the pinion from mesh with the engine gear upon starting of the engine; releasable means for holding the pinion in mesh with the engine gear to preclude premature de-meshing; and means responsive to a source of energy remote from the starter and rendered operative solely as a consequence to the engine operating under its own power for disabling said holding means to free the pinion for retraction.

3. In an engine starter: a pinion movable to and from an operative position; means for automatically projecting the pinion to its operative position and for automatically retracting the

pinion from its operative position; means for holding the pinion in mesh with the engine fly-wheel; and means wholly independent of the starter for disabling said holding means to free the pinion for retraction.

4. In an engine starter: an engine driving member movable to and from an operative position; means for automatically propelling the engine driving member to its operative position and for automatically retracting the engine driving member from its operative position; an annular shoulder carried by the engine driving member; a holding member engageable with said shoulder to hold the engine driving member in operative position while enabling free rotation thereof; and means responsive to a force wholly outside the starter for moving said holding member to an inactive position freeing the engine driving member for retraction. 10 15 20

5. In a starter for internal combustion engines having a ring gear: a pinion movable to and from mesh with the ring gear; means for automatically propelling the pinion into mesh with the ring gear, for turning the pinion to drive the ring gear and crank the engine and for automatically retracting the pinion out of mesh; an annular shoulder on the pinion; a holding member engageable with said shoulder to hold the pinion in mesh with the ring gear; and means responsive to a source of energy remote from the starter for moving said holding member to an inoperative position freeing the pinion for retraction. 20 25 30

6. In a starter for internal combustion engines; an engine driving member movable to and from an operative position engaging an engine part to effect cranking of the engine; means for automatically propelling the engine driving member to its operative position and for automatically retracting the same from its operative position; a holding member for holding the engine driving member in engagement with the engine part; and means responsive to engine suction for moving said holding member to an inoperative position. 35 40 45 48

7. In a starter for internal combustion engines: an engine driving member movable to and from an operative position engaging an engine part to effect cranking of the engine; means for automatically propelling the engine driving member to its operative position and for automatically retracting the same from its operative position; a holding member for holding the engine driving member in engagement with the engine part; and means responsive to pressure in the oil line of the engine for moving said holding member to an inoperative position. 50 55

8. In a starter for internal combustion engines: an engine driving member movable to and from an operative position engaging an engine part to effect cranking of the engine; means for automatically propelling the engine driving member to its operative position and for automatically retracting the same from its operative position; a holding member for holding the engine driving member in engagement with the engine part; and electromagnetic means adapted to be energized from the generator of the engine to move the holding member to an inoperative position. 60 65 70

JOHN W. FITZ GERALD.
